UNITED STATES PATENT OFFICE.

WILLIAM GLASS, OF LONDON, ENGLAND.

APPARATUS FOR PLAYING A TABLE GAME.

1,126,980.

Specification of Letters Patent. Patented Feb. 2, 1915.

Application filed September 11, 1913. Serial No. 789,329.

To all whom it may concern:

Be it known that I, WILLIAM GLASS, a subject of the King of Great Britain and Ireland, and resident of London, England, have invented a certain new and useful Improvement in Apparatus for Playing a Table Game, of which the following is a specification.

This invention relates to a table game of skill of the type wherein disks are projected upon a playing area formed upon a smooth surface, detachable or otherwise, suitably marked out. According to this invention, the disks are projected by elastic means.

15 To render the following description clear, a sheet of drawings is appended, in which:—

Figure 1 is a partial plan view of the main part of the apparatus. Figs. 2 and 3 are modifications hereinafter referred to. Fig.

20 Fig. 4 is a view of a roller and attachment. Fig. 5 is a perspective view of the attaching detail. Fig. 6 illustrates a feature hereinafter referred to. Fig. 7 is a modification or alternative of Fig. 5. Fig. 8 is a side elevation of a disk used with this game apparatus.

The playing area may be formed on a roller sheet *a* which is furnished with a desired playing figuration; the sheet is mounted upon rollers such as *b* at one or each end which have projections *c* at each extremity whereby a twisted metal clip *d*—more clearly seen in Fig. 5—or other means may secure same to the table or the like. The clip may be in the form of bent wire *e* as seen in Fig. 7. A permanent table with the playing figuration marked thereon may be used as an alternative.

40 A bow device is adapted to be secured to the table at the player's end, said bow being an approximately semicircular or curved-shaped member *f* furnished with a suitable elastic strip *g* between its extremities; or, as a modification, the bow may be dispensed 45 with and the elastic strip attached directly to clips or clamps which may be secured to the table edge.

As a preferred construction the bow *f* aforesaid is pivotally attached to the table 50 in order that the position of the elastic strip *g* may be varied at will in accordance with the direction in which it is intended to project the disks. The pivoting of the bow may be at one side edge of the table or centrally 55 of the bow at the bottom of the table, and consists, in one form, of a suitable attaching

block or the like *h* which is or may be clamped by a vise-clamp or other means to the table, which may at the same time clamp one end of the sheet *a* when same is used. 60 The bow *f* is preferably constructed of flat wood as in Fig. 1 formed of detachable portions for convenience of packing and transit, said portions fitting into the pivoted part *i*. Or, in another form, the curved arms of the 65 bow may be thin metal members *j*—see Fig. 2—fitting into tubular or other sockets *k* in or on a portion similar to *i* pivoted to the aforesaid pivotal clamp member *h*. In the case of a member such as *j* the flexible 70 strip *g* may be inextensible and the elasticity acquired from the springiness of the thin metal members. Alternatively, the bow *j* may be as one whole and not divided—see 75 Fig. 3.

In the instance when the bow is dispensed with, one or both of the clamps which are attached to the table (and hold the elastic strip) may be adjustable thereon with or without the intervention of roller or slide 80 devices.

The disks *l* are formed with projections, such as knobs *m* or curved grooved raised portions.

In play, the player slides the disk *l* under 85 the elastic or other strip *g* (which is adjusted in height from the table surface as desired by means of pieces *o*) until the projection *m* encounters the said strip *g*; then, by sliding farther and distending the elastic 90 strip as depicted in Fig. 1, or pulling together the bow extremities, the disk may be projected on to the playing area. The strip *g* has been previously adjusted according to the player's skill in order that the disk 95 may be projected at any angle with relation to the table edges and playing area. The mode of attaching the strip *g* to the bow may be as found convenient; for instance, in Fig. 1 it is attached to a screw or the like *n*, 100 or when a metal bow *j* is employed the extremities may be bent as at *p*—Fig. 6.

It is understood that various modifications of the foregoing constructions may be adopted within the scope of the present invention.

Having now described my invention, what I claim as new and desire to secure by Letters Patent of the United States is:—

1. A projecting device for game apparatus including in combination with a support, an attaching block adapted to be se-

cured to said support, a resilient bow member pivotally attached at its intermediate portion to said attaching block, and means for connecting the opposite extremities of
5 the bow member.

2. A game apparatus including in combination with the playing area and a projectile member, a device for projecting said member over the playing area comprising a
10 spring bow member, a flexible strip connect-

ing the extremities of the bow, an attaching block for the bow, and a pivotal connection between the bow and attaching block.

In testimony whereof I have affixed my signature in presence of two witnesses.

WILLIAM GLASS.
